(57) **CLAIM**

The ornamental design for a firearm, as shown and described.

DESCRIPTION

FIG. 1 is a side perspective of a firearm according to the novel design.

FIG. 2 is a side perspective of a firearm according to the novel design.

FIG. 3 is a side elevational perspective of a firearm according to a novel design.

FIG. 4 is a side elevational perspective of a firearm according to the novel design.

FIG. 5 is a top perspective of a firearm according to the novel design.

FIG. 6 is a bottom perspective of a firearm according to the novel design.

FIG. 7 is a front perspective of a firearm according to the novel design.

FIG. 8 is a back perspective of a firearm according to the novel design.

FIG. 9 and FIG. 10 are side perspective views of the rear stock of the firearm according to the novel design.

FIG. 11 is a close-up side perspective of a firearm according to the novel design.

FIG. 12 is a close-up side perspective of a grip of a firearm according to the novel design.

FIG. 13 is a close-up elevational perspective of a firearm according to the novel design.

FIG. 14 is close-up side perspective of a firearm according to the novel design.

FIG. 15 is a close-up barrel of the exemplary firearm incorporating the novel design together with some of the environment or background as depicted in the drawings.

Any written matter appearing in the Figures is disclaimed and does not form a part of the novel design.

The broken lines included in the drawings depict elements that are not part of the claimed design.

1 Claim, 11 Drawing Sheets
